Primary Examiner—Jeffrey Asch

(57) **CLAIM**

I claim the ornamental design for the keys for a handset, as shown and described.

DESCRIPTION

FIG. 1 is a front view of the keys for a handset; and, FIG. 2 is a perspective front view thereof. The portion of the keys for a handset shown in broken lines is for illustrative purposes only and forms no part of the claimed design.

1 Claim, 2 Drawing Sheets Fig. 1

Fig. 2
